UNITED STATES PATENT OFFICE.

ARCHIBALD McNICOL, OF YPSILANTI, MICHIGAN.

HOOK AND EYE.

SPECIFICATION forming part of Letters Patent No. 694,777, dated March 4, 1902.

Application filed December 19, 1900. Serial No. 40,391. (No model.)

To all whom it may concern:

Be it known that I, ARCHIBALD McNICOL, a citizen of the United States of America, residing at Ypsilanti, in the county of Washtenaw and State of Michigan, have invented certain new and useful Improvements in Hooks and Eyes, of which the following is a specification, reference being had therein to the accompanying drawings.

10 My invention relates to new and useful improvements in hooks and eyes for wearing apparel, &c.; and the object of my invention is to construct a simple, economical, and durable hook and eye which reduces the overlapping of the parts and the side play of the eye to a minimum and at the same time allows the hook and eye to be made flatter and rendered more safe from accidental disengagement, at the same time permitting the 20 parts to be readily disengaged when desired by a single continuous stripping action.

A further object of my invention is to so construct the hook and eye that the eye will be positively guided upon the hook and caused 25 to have a combined sliding and twisting movement to release the same; and the invention further consists in such other features as will readily appear from the ensuing description and which are attained by virtue of the construction shown in the accompanying drawings, in which—

Figure 1 is a plan view of my improved hook and eye hooked together. Figs. 2 and 3 are front and side elevations, respectively, 35 of the eye detached. Figs. 4 and 5 are front and side elevations, respectively, of the hook detached. Figs. 6 and 7 are modified constructions thereof. Fig. 8 is an elevation of the hook and eye as in the act of being 40 disengaged. Fig. 9 is a perspective view of the hook and eye as in use, illustrating the stripping action.

As shown in the drawings, A is the hook, and B the eye, each composed of a single continuous strand of wire, the hook A being composed of the bill a, the base portion b, having the anchor-eyes c formed thereon, and the spring tongue or guard d, substantially in line with the outer arm or one side of the bill and 50 spaced therefrom a distance slightly less than

the thickness of wire comprising the eye. The bill a is spread apart considerable at its base, so as to allow the eye but very little side play when engaged, and is bent to one side of the center line z z of the hook, so that the 55 arm e will form quite an angle therewith, as shown in Fig. 1, said arm terminating in a shoulder e' and anchor-eye c, and thence continuing diagonally across to form the base portion and bent back upon itself to form an 60 anchor-eye and the guard d, while the arm f' of the bill is bent downward to form a shoulder and diagonally across to form the base portion, having its end formed into an anchor-eye, as shown. It will thus be seen that the 65 hook is provided with the two transversely-inclined members e f' at substantially right angles to each other, the arm e forming part of the bill and the member f' a portion of the base, so that in disengaging the parts the eye 70 will be caused to be given a combined sliding and twisting movement in releasing the same by reason of said oppositely-inclined members and released in an inverted position, as shown in Fig. 8. 75

B is the eye, composed of the rounded portion g, terminating in the substantially parallel members h h' and the arm i at substantially right angles thereto and having the anchor-eye i' formed at its junction with the 80 member h, the opposite ends of said continuous strand of wire being provided with anchor-eyes j. It will also be noticed that the eye is provided with a slight compound bend, as shown at k in Fig. 3, to aid in the twisting 85 movement of the hook in releasing the same.

Fig. 8 shows the eye after it has completed its twisting movement in the act of releasing the same, it simply being held by the spring-tongue, and it will be noticed that the eye is 90 in a position at right angles to its normal position, as indicated in dotted lines, and in an inverted position.

Figs. 6 and 7 show modified constructions which would obviously suggest themselves 95 and are deemed to be within the spirit of my invention. It will be noticed that the opposing inclines of the members e and f' are still maintained, although the wires constituting the base portion do not cross each other. 100

Having thus fully described my invention, it is intended to operate as follows: The hook and eye being engaged in the usual manner, to disengage the same the operator by a combined outward and downward pull (or continuous stripping action where a number of hooks are used) causes the same to be released, and it will be seen that the parts are so constructed that the eye will turn back upon itself in sliding down the inclined side of the bill by reason of the rounded portion of the eye sliding in contact with the inclined base portion of the hook, while the straight portion of the eye slides down the oppositely inclined side of the bill, thus causing a positively-guided twisting movement of the eye, which turns the eye over the bill of the hook and then releases it from the tongue, which is partly to one side of the bill, and as the forward upper corner of the eye is made fast to the goods and is between the pulling part of the eye and the goods it tends to aid the eye in its reverse movement to release the same.

25 What I claim as my invention is—

1. In a hook and eye, a hook provided with a tapering bill bent to one side of the center line of the hook, and having one of its sides inclined, and a guard coöperating with said bill to one side thereof and at an angle to the inclined side thereof.

2. A hook for wearing-apparel, &c., comprising a base, a bill bent to one side of the center line of the base and substantially parallel therewith, having one of its sides inclined transversely of the hook, and a spring-tongue formed integral with the base, said tongue being oppositely inclined to said bill and terminating in line with the outer arm of said bill and coöperating therewith.

3. In a hook and eye, a hook provided with a spring tongue or guard, and a bill having one of its sides laterally inclined from its base up to the point of nearest approach of the tongue or guard, said tongue or guard overlapping the bill at one side thereof and arranged at an angle thereto whereby on tilting the eye sidewise it will be caused to slide down said incline and pass between said bill and guard.

4. In a hook and eye, a hook having a tongue and a bill formed integral with the base, said bill and tongue being bent to one side of the center line of the hook and overlapping each other, said bill having one of its sides inclined and said tongue bent at an angle thereto at one side thereof whereby said eye will be caused to slide down the inclined side of said bill and by the same, and finally released by said tongue.

5. In a hook and eye, a hook having a base and an inclined spring-tongue at one side thereof, a bill having one of its sides inclined from the base to the point of nearest approach of the tongue and at an angle thereto, and having a portion of its base bent at substan-

tially right angles to said inclined side of said bill, and an eye bent to coöperate with said reversely-inclined bill and base portion whereby said eye will be tilted sidewise and caused to slide down the inclined side of the bill in releasing the same.

6. In a hook and eye, a hook provided with a bill bent to one side, of the center line of the hook and at an angle thereto, a spring-tongue coöperating therewith and bent at an angle thereto, with their meeting ends overlapping at one side thereof, whereby said eye will be caused to slide down the inclined side of the bill and by the same and to be finally released by said tongue.

7. In a hook and eye, a hook provided with a spring tongue or guard inclined from its base to one side thereof, and a bill having one of its sides laterally inclined from its base to the point of nearest approach of the guard and overlapping the same at one side thereof, said base portion having one of its members bent at substantially right angles to the inclined side of the bill, and an eye coöperating with said reversely-inclined portions whereby in disengaging the parts, the eye will be tilted sidewise and caused to slide down the inclined side of said bill and by the same, to be finally released by said spring-tongue.

8. In a hook and eye, a hook formed with a base portion and a rearwardly-extending bill or projection bent to one side of the center line of the hook, and a forwardly-extending tongue or projection bent at an intersecting angle thereto and coöperating therewith, also bent to one side of the center line of the hook, said projections being separated from each other by an interval less than the thickness of the eye, the opposite sides of said bill and base portion being reversely inclined, whereby said eye will be tilted sidewise and caused to slide down the inclined side of said bill to release the same.

9. In a hook and eye, a hook formed with a base portion, and provided with a bill extending upwardly from the base and bent to one side of the center line thereof, and a spring-tongue overlapping said bill at one side thereof and coöperating therewith, said bill having one of its sides inclined and crossing its opposing base member at an angle thereto, and an eye provided with the circular end portion *g* and the upwardly-curved portion *k* coöperating with the reversely-inclined portions of the base and bill, whereby said eye will be caused to tilt sidewise and slide down the inclined side of said bill and be finally released by said tongue.

10. In a hook and eye, a hook composed of the bill *a*, and base *b*, said hook having the opposing inclines *e*, *f*', formed by the bill and base, respectively, the guard *d* coöperating with said bill to one side thereof, and the eye *B* having the rounded portion *g* and the reversely-curved portion *k* adapted to coöperate with the opposing inclines of the hook,

whereby a combined sliding and tilting motion will be imparted to said eye to release the same, substantially as described.

11. In a hook and eye, an eye having the rounded portion *g*, reversely-curved portion *k* and the anchor-eye *i*, whereby in releasing the same, said anchor-eye will be in the direct line of the pull and cause a combined

sliding and tilting motion to be imparted to said eye.

In testimony whereof I affix my signature in presence of two witnesses.

ARCHIBALD McNICOL.
